UNITED STATES PATENT OFFICE.

PAUL J. McCULLOUGH, OF ST. LOUIS, MISSOURI, ASSIGNOR, BY MESNE ASSIGNMENTS, TO SCULLIN STEEL CO., OF ST. LOUIS, MISSOURI, A CORPORATION OF DELAWARE.

ARTICULATED CAR.

Application filed April 14, 1926. Serial No. 101,890.

The present invention relates to articulated cars.

More particularly the present invention relates to railroad cars and has for one of its objects the provision of an improved structure wherein two or more car bodies are mounted in articulated relationship with one another, the adjacent ends of said cars having trucks in common.

The present invention has been illustrated and will be described in connection with three-truck cars, two car bodies being provided with three trucks, the adjacent ends of said cars being supported by one of said trucks. Cars of this type have decided advantages, particularly when used upon tracks having a number of relatively sharp curves, which advantages need not be referred to in detail herein.

A further object of the present invention is to provide a structure of car which is relatively cheap and simple to manufacture and which will distribute the loads uniformly.

A further object is to provide a car structure which is cheap and which has improved safety over prior constructions.

Further objects will appear as the description proceeds.

Referring to the drawings—

Figure 1 is a view in side elevation of a car having two car bodies supported by three trucks;

Figure 2 is a view on an enlarged scale of the central portion of the car shown in Figure 1, parts being broken away for purposes of clarity; and

Figure 3 is a sectional view taken along the planes indicated by the arrows 3—3 of Figure 2.

The car shown in Figure 1 comprises the two car bodies 1—1, which at their unadjacent ends are provided with the trucks 2—2, which may be of usual construction. Adjacent ends of said car bodies 1—1 are supported by a truck 3, which is of special construction. As at present preferred, the truck 3 is a three-axle truck, the journal boxes for supporting said three axles being indicated by the numerals 4—4 in Figure 1. Said axles are equi-spaced, and located symmetrically between said axles are the bolster spaces 5—5. Within said bolster spaces are bolsters 6, which bolsters may be carried by any preferred type of spring 6'.

The numerals 7—7 indicate housings (which may be castings) secured to the draft sills 8—8, which housings 7—7 provide sockets for the pivotal mounting of the head portions 9—9 of the strap 10, said head portions being extended to a lower level than the remaining portion of the strap 10. Abutments 11—11 secured to the housings 7—7 and to the draft sills 8—8 maintain the strap or connecting rod 10 with its head portions 9—9 in proper relationship with the housings 7—7.

Disposed directly above the center of each of the bolsters 6—6 is a center plate 12, which may be of usual construction. The axes of said center plates 12—12 will be in substantial coincidence with the axes of the corresponding head portions 9—9 of the strap 10. The side frames 3—3 on the two sides of the middle truck are linked together at their inner ends at a region over the journal box middle axle and are held in position by a pin or bolt indicated by the numeral 13, which is sufficiently loose to permit universal movement within limits sufficient to accommodate any combination of lateral and vertical movements such as are caused by curves and inequalities in the tracks. Inasmuch as the strap or connecting rod 10 holds the center plates 12—12 at a fixed distance apart, there can be no separation of the side frames of the middle axle even though the pin or bolt 13 is omitted.

The present invention has the advantage that relatively sharp curves may be rounded with a minimum of swing and a minimum of tendency for the car wheels to climb the rails. No more couplers, draft gears and the like are required than in cars of the usual length.

Due to the fact that there are two center plates on the middle truck, said middle truck will always tend to keep its proper position on the rails. Let it be assumed that the middle truck is on a curve with the flange of a wheel at one end of the truck resting against the outer rail and the flange of a wheel on the other end of the truck resting against the inner rail, in which position the truck would have a tendency to climb the rail or leave the track. If the car be moved in one direction, the flanges of the three outside wheels would all roll against the outer rail of the curved track, and if the car be moved in the opposite direction the flanges of the

three inner wheels would all roll against the inner rail of the curved track, whereby a positive action is had in properly positioning said middle truck upon the rails.

5. By reason of the present invention the two-truck bolsters of the middle truck divide the load impressed by the adjacent portions of the two car bodies, and the effect of inertia in causing the wheels to climb the rails 10 is minimized.

Though a preferred embodiment of the present invention has been described in detail, it will be clear that many modifications will occur to those skilled in the art. It is 15 intended to cover all such modifications that fall within the scope of the appended claims.

What is claimed is—

1. In combination, a plurality of car bodies placed end for end, the adjacent ends of said 20 car bodies being provided with socket portions, a connecting rod having head portions mounted within said socket portions, and a single truck for supporting said adjacent ends of said car bodies, said truck having three axles and having a pair of bolsters disposed symmetrically with reference to the 25 center axle.

2. In combination, a plurality of car bodies placed end for end, the adjacent ends of 30 said car bodies being provided with socket portions, a connecting rod having head portions mounted within said socket portions, and a single truck for supporting said adjacent ends of said car bodies, said truck having 35 three axles and having a pair of bolsters

disposed symmetrically with reference to the center axle, the axes of said socket portions being disposed over the middles of said bolsters.

3. In combination, a pair of car bodies, a connecting rod for connecting adjacent ends of said car bodies, said car bodies and said connecting rods being provided with interfitting parts forming pivotal connections, and a single truck for carrying the two adjacent 40 ends of said car bodies, said truck being provided with three axles and with a pair of bolsters, the mid points of said bolsters being disposed in the axes of pivotal connection of said connecting rod with said car 45 bodies.

4. In combination, a pair of car bodies, a connecting rod for pivotally joining the adjacent ends of said car bodies together, and a single truck for carrying said adjacent 50 ends of said car bodies, said truck being provided with a pair of center plates and a pair of bolsters.

5. In combination, a pair of car bodies, a connecting rod for pivotally joining the adjacent ends of said car bodies together, and a single truck for carrying said adjacent 60 ends of said car bodies, said truck being provided with a pair of center plates and a pair 65 of bolsters, said center plates being disposed symmetrically over the centers of said bolsters.

Signed at St. Louis, Missouri, this 9th day of April, 1926.

PAUL J. McCULLOUGH.
